METAL RECOVERY PROCESS

Louis B. Wernaer and Orville F. Hill, Richland, Wash., assignors to the United States of America as represented by the United States Atomic Energy Commission

No Drawing. Application June 11, 1945,
Serial No. 598,908

11 Claims. (Cl. 23—14.5)

The present invention is directed to a method for the recovery of plutonium from solid compositions containing the same. More particularly, it is related to a novel process for the recovery of plutonium in concentrated form from solid compositions containing columbic oxide by the formation of volatile fluorides of certain fission products and columbium followed by the formation of a volatile fluoride of plutonium and the subsequent recovery thereof from the relatively nonvolatile fluorides of other impurities associated therewith.

It is known that plutonium can be produced in small quantities by the bombardment of uranium metal with slow or thermal neutrons. The designation "plutonium" or "element 94" as used throughout the present description refers to the transuranic element having an atomic number of 94. The expression "94²³⁹" means the isotope of element 94 having an atomic weight or mass of 239. Similarly, the terms "element 93" or "Np" refer to the new element known as neptunium having an atomic number of 93.

Uranium metal is composed of three isotopes, namely, U²³⁴, U²³⁵, and U²³⁸, the latter being present in excess of 99 percent of the whole. When U²³⁸ is subjected to the action of slow or thermal neutrons, a third isotope, U²³⁹, is produced having a half-life of 23 minutes and undergoes beta decay to Np²³⁹ which decays further by beta radiation with a half-life of 2.3 days to yield plutonium. In addition to the formation of the transuranic elements, neptunium and plutonium, there are simultaneously produced other elements of lower atomic weight known as fission fragments. These fission fragments are composed of two distinct element groups, i. e., a light and heavy element group. The light group contains elements having atomic numbers of between about 35 and 46 while the heavy group is composed of elements of atomic numbers varying between about 51 and 60. The elements of these groups as originally produced are in the form of highly unstable isotopes, and by beta radiation quickly transform themselves into isotopes of these various elements having longer half-lives. The resulting materials are commonly known as fission products.

The various radioactive fission products have half-lives ranging from a fraction of a second to thousands of years. Those having very short half-lives may be substantially eliminated by ageing the material for a reasonable period before handling. Those with very long half-lives do not have sufficiently intense radiation to endanger personnel protected by moderate shielding. On the other hand, the fission products having half-lives ranging from a few days to a few years have dangerously intense radiations which cannot be eliminated by ageing for practical storage periods. These products are chiefly radioactive isotopes of Sr, Y, Zr, Cb, and Ru of the light group and Te, I, Cs, Ba, La, Ce, and Pr of the heavy group.

It may readily be seen that plutonium produced as generally set forth above is contaminated with considerable quantities of uranium and fission products. In fact, the plutonium usually constitutes only a very minor por-

2

tion of the irradiated mass, i. e., less than one percent thereof. In view of such a low concentration of plutonium in the irradiated metal, it becomes apparent that the procedure employed to recover that element must be highly efficient in order to be at all practicable.

There have been devised a number of procedures for the removal and concentration of plutonium from extremely dilute solutions thereof. In general, such methods involve the formation of various insoluble compounds in said dilute solutions capable of carrying plutonium in the reduced state. The carrier precipitate and plutonium thus obtained are then dissolved and the plutonium oxidized to PuO₂⁺⁺ in which state of oxidation it is soluble in the presence of said carrier. Under these conditions, the plutonium remains in solution and the fission products are removed when the carrier is added. Thereafter, the dissolved plutonium is reduced to a valence state in which it is carriable by the aforesaid carrier and removed from solution in the form of a carrier precipitate which may again be dissolved and the plutonium purified further if considered necessary or desirable by repeating the above cycle. This procedure, however, is obviously cumbersome and time consuming since it requires a number of such steps in order to effect a substantial removal of fission products and other impurities.

Moreover, certain fission products, notably columbium and zirconium, are extremely difficult to remove from plutonium-containing solutions of the aforesaid type by the use of carriers in accordance with the method generally outlined above.

Of the various materials suitable for use as carriers of plutonium in the reduced state, in accordance with the procedure generally set forth above, it has previously been found that columbic oxide is admirably suited for this purpose. However, it has also been observed that columbic oxide, like the other compounds used as carriers in such a process, carries a considerable quantity of impurities, chiefly fission products, together with the plutonium, and hence the procedure of carrying plutonium in its reduced state, dissolving the precipitate thus formed,

oxidizing the plutonium to a noncarriable state, removing the fission products by precipitating the columbic oxide carrier, etc., had to be repeated several times before the plutonium could be obtained in a substantially pure condition.

It is an object of the present invention to provide a single step process for obtaining plutonium values in high concentration from acid solutions of neutron bombarded uranium.

It is a further object of our invention to provide a method that will effectively separate plutonium from the fission products and other impurities normally associated therewith.

Additional objects of our invention will be apparent as the present description proceeds.

It has now been discovered that plutonium can be obtained in a highly concentrated and purified state in the form of its volatile fluoride from columbic oxide carrier precipitates by means of a procedure involving selective hydrofluorination and fluorination processes.

The recovery and concentration of plutonium in accordance with the process of the present invention is based upon the fact that columbic oxide is converted to volatile columbium pentafluoride when the former is subjected to the action of hydrogen fluoride whereas plutonium in the tetravalent state under the same conditions is converted to plutonium tetrafluoride, a substantially non-volatile compound. After the columbium has been removed as the fluoride, the residue is contacted with elemental fluorine to convert the plutonium tetrafluoride contained therein to a higher volatile fluoride, probably the penta or hexafluoride, or a mixture thereof, and hence

70

may be readily separated as such from the residual impurities whose fluorides are substantially nonvolatile.

In accordance with a preferred embodiment of our invention, neutron bombarded uranium is first dissolved in a suitable acid such as, for example, nitric acid. Since the plutonium present in the resulting solution exists in different valence states, it is preferable to subject said solution to the action of a reducing agent such as, for example, sodium nitrite, in order to convert completely the dissolved plutonium to a carriable state (valence state not above 4). To the solution thus treated is then added a preformed columbic oxide precipitate either in the anhydrous or hydrated form, thereby causing the substantially complete precipitation of plutonium. Since the dissolved hexavalent uranium is unaffected by the aforesaid reduction step, it is not removed from solution by the columbic oxide carrier. However, a substantial amount of radioactive fission products, particularly columbium and zirconium are brought down. Additional fission products present at this stage that are capable of forming volatile fluorides are, antimony, ruthenium, and element 43. The columbic oxide precipitate thus obtained is next dried and thereafter placed in a suitable fluorination reactor. The dried precipitate is then subjected, at elevated temperatures, for example, of the order of about 500° C., to the action of hydrogen fluoride, preferably in the anhydrous condition, whereupon the columbium present together with such elements as antimony, ruthenium, and element 43 are converted to their volatile fluorides which are readily separated from the remainder of the solid mass. Other fission products such as, bromine and iodine are also volatilized at this point. The residue which consists essentially of plutonium tetrafluoride and substantially nonvolatile fission product fluorides including the fluorides of rubidium, strontium, barium, yttrium, lanthanum, cesium, and cerium are then contacted with fluorine, preferably in the anhydrous state, at temperatures of about 315° C. or above, and preferably between about 425 and 500° C., to convert the lower plutonium fluoride to a higher volatile fluoride, (probably a fluoride of plutonium in valence state above 4) which is collected at temperatures below 315° C. in a suitable receiver. The molybdenum and neptunium present may be separated from the plutonium-containing mass by treatment with fluorine at temperatures between about 250° and 300° C. prior to formation of the higher fluoride of plutonium. Any columbium which is not removed on reaction of the original carrier precipitate with hydrogen fluoride under the above stated conditions will ordinarily be removed along with the plutonium hexafluoride when the aforesaid residue is subjected to the action of elemental fluorine, after which the columbium may be separated from plutonium by fractional distillation owing to a difference of approximately 70° C. in the boiling points of their fluorides.

Our invention may be further illustrated by the following specific example:

Example

To 25 ml. of a nitric acid solution of neutron irradiated uranium, which has previously been treated with sodium nitrite to reduce the plutonium present therein to a carriable state, is added 1 g. of a preformed columbic oxide precipitate. The resulting mixture is agitated for ten minutes, after which it is allowed to settle and the columbic oxide carrier precipitate separated by centrifugation. The solid residue thus obtained, and which contains approximately 50 mg. of plutonium together with fission products, is next placed in a drying oven at a temperature of about 100° C. and allowed to remain until substantially anhydrous. Thereafter the dried columbic oxide carrier precipitate is placed in a nickel-tube fluorination reactor of conventional design after which anhydrous hydrogen fluoride is introduced at a rate of approximately 0.5 liter per hour for a period of two hours at 500° C. At the end of this period all of

the columbium is converted to columbic pentafluoride and is completely volatilized together with bromine and iodine, and the fluorides of zirconium, ruthenium, and antimony. Under these conditions the plutonium present is converted to plutonium tetrafluoride which is nonvolatile and is left as a residue in the reaction chamber together with such fission products as barium, strontium, neptunium, molybdenum, yttrium, lanthanum, cesium, and cerium. Anhydrous fluorine is next introduced at a rate of about 0.3 liter per hour at a temperature of between 250-300° C. whereupon any neptunium and molybdenum which might be present are converted to their volatile fluorides and thus removed. The temperature is then increased to about 500° C. under which conditions the plutonium tetrafluoride is transformed to a volatile fluoride and is collected in a suitable receiving vessel at a temperature below 315° C. The remaining fission products, most of which are in the form of their fluorides, are left as a residue in the reaction chamber. The plutonium recovered in this manner represents approximately 90-95 percent of that originally present in the columbic oxide carrier precipitate.

It will be apparent to those skilled in the art that the method of recovering plutonium as generally set forth above provides a simple and practical procedure for the procurement of high concentrations of plutonium in a single step. Also, it will be further apparent that by the utilization of such a procedure, a relatively high degree of purification of plutonium with respect to fission products and other impurities is obtainable.

While this invention has been illustrated by certain restricted applications thereof, it is not desired to be specifically limited thereto, since it is manifest to those skilled in the art to which the present invention is directed that it is susceptible to numerous alterations and modifications without departing from the scope thereof. For example, anhydrous liquid hydrogen fluoride instead of gaseous hydrogen fluoride may be employed in the formation of the desired fluorides in our process. In general, it may be said that any process for the separation of plutonium from columbic oxide carrier precipitates and the impurities associated therewith by formation of volatile fluorides of said columbic oxide and impurities followed by formation of a volatile fluoride of plutonium and subsequent recovery thereof, is to be construed as lying within the scope of our invention.

What is claimed:

1. The process of recovering a volatile fluoride of plutonium in concentrated and purified form from a solid composition containing columbic oxide, plutonium values, and fission product values which comprises contacting said composition with hydrogen fluoride, heating said composition and hydrogen fluoride to a temperature of about 500° C. to convert the plutonium values to nonvolatile plutonium tetrafluoride and to volatilize the columbium values as columbium pentafluoride together with volatile fission product fluorides, contacting the residual nonvolatile fission product fluorides and plutonium tetrafluoride with fluorine, heating this mixture of plutonium tetrafluoride, fission product fluorides, and fluorine to a temperature of between 315°-500° C. to form a volatile fluoride of plutonium which is immediately volatilized leaving as a residue the substantially nonvolatile fission product fluorides, and recovering said volatile fluoride of plutonium.
2. The process of recovering a volatile fluoride of plutonium in concentrated and purified form from a solid composition containing columbic oxide, plutonium values and fission product values which comprises contacting said composition with anhydrous hydrogen fluoride, heating said composition and hydrogen fluoride to a temperature of about 500° C. to convert the plutonium values to nonvolatile plutonium tetrafluoride and to volatilize the columbium values as columbium pentafluoride together with volatile fission product fluorides, contacting the residual

nonvolatile fission product fluorides and plutonium tetrafluoride with anhydrous fluorine, heating this mixture of plutonium tetrafluoride, fission product fluorides, and fluorine to a temperature of between 315°-500° C. to form a volatile fluoride of plutonium leaving as a residue the substantially nonvolatile fission product fluorides, and recovering said volatile plutonium fluoride.

3. The process of recovering a volatile fluoride of plutonium in concentrated and purified form from a solid composition containing columbic oxide, plutonium values and fission product values which comprises contacting said composition with hydrogen fluoride, heating said composition and hydrogen fluoride to a temperature of about 500° C. to convert the plutonium values to nonvolatile plutonium tetrafluoride and to volatilize the columbium values as columbium pentafluoride together with volatile fission product fluorides, contacting the residual nonvolatile fission product fluorides and plutonium tetrafluorides with fluorine, heating this mixture of plutonium tetrafluoride, fission product fluorides, and fluorine to a temperature of between 425°-500° C. to form a volatile fluoride of plutonium leaving as a residue the substantially nonvolatile fission product fluorides, and recovering said volatile plutonium fluoride.

4. The process of recovering a volatile fluoride of plutonium in concentrated and purified form which comprises removing plutonium values from an acid solution containing uranium values in the hexavalent state, fission product values, and plutonium values in the tetravalent state by adding thereto columbic oxide, removing the resultant precipitate which contains plutonium values and fission product values, drying said precipitate to a substantially anhydrous condition and thereafter subjecting said precipitate to the action of hydrogen fluoride, heating the mixture of said precipitate and hydrogen fluoride to a temperature of about 500° C. to convert the plutonium values to nonvolatile plutonium tetrafluoride and to volatilize columbium pentafluoride and volatile fission product fluorides, contacting the residual nonvolatile fission product fluorides and plutonium tetrafluoride with fluorine, heating this mixture of plutonium tetrafluoride, fission product fluorides, and fluorine to a temperature of between 315° and 500° C. to form a volatile fluoride of plutonium leaving as a residue the substantially nonvolatile fission product fluorides, and recovering said volatile plutonium fluoride.

5. The process of recovering a volatile fluoride of plutonium in concentrated and purified form from a solid composition containing columbic oxide, plutonium values and fission product values which comprises hydrofluorinating said composition to convert the plutonium values to nonvolatile plutonium tetrafluoride, volatilizing columbium values as columbium pentafluoride together with volatile fission product fluorides by subjecting the resultant hydrofluorinated mass to a temperature of about 500° C., fluorinating the nonvolatile residue thus obtained which comprises essentially plutonium tetrafluoride and nonvolatile fission product fluorides to convert said plutonium tetrafluoride to a volatile fluoride of plutonium, separating the latter from the remainder of the nonvolatile fluorinated residue by heating said residue to the volatilization temperature of said volatile plutonium fluoride leaving a residue comprising essentially nonvolatile fission product fluorides, and thereafter recovering said volatile plutonium fluoride.

6. The process of recovering a volatile fluoride of plutonium in concentrated and purified form from a solid composition containing columbic oxide, plutonium values and fission product values which comprises subjecting said composition to the action of anhydrous hydrogen fluoride at a temperature of about 500° C. to convert the plutonium values to nonvolatile plutonium tetrafluoride and to volatilize columbium values as columbium pentafluoride together with volatile fission product fluorides, subjecting the nonvolatile residue thus obtained to the

action of anhydrous fluorine at a temperature of above about 315° C. to form a volatile fluoride of plutonium leaving as a residue the nonvolatile fission product fluorides, and recovering said volatile plutonium fluoride.

5 7. The process of recovering a volatile fluoride of plutonium in concentrated and purified form from a solid composition containing columbic oxide, plutonium values and radioactive fission products, which comprises subjecting said composition to the action of anhydrous hydrogen fluoride at a temperature of about 500° C. to convert the plutonium values to nonvolatile plutonium tetrafluoride and to volatilize columbium values as columbium pentafluoride together with the volatile radioactive fission product fluorides, fluorinating the residual nonvolatile radioactive fission products and plutonium tetrafluoride at a temperature of between about 425° and 500° C. to form a volatile fluoride of plutonium leaving as a residue the substantially nonvolatile radioactive fission product fluorides, and recovering said volatile plutonium

20 fluoride.

8. The process of recovering a volatile fluoride of plutonium in concentrated and purified form from a solid composition containing columbic oxide, plutonium values and fission product values which comprises contacting said composition with hydrogen fluoride to convert said plutonium values to plutonium tetrafluoride, and said fission product values and columbium values to fission product fluorides and columbium pentafluoride respectively, heating the resulting hydrofluorinated mass to a temperature at which plutonium tetrafluoride is non-volatile and that is the volatilization temperature for the columbium pentafluoride and volatile fission product fluorides thus produced, fluorinating the resultant non-volatile residue, separating the volatile fluoride of plutonium thus formed from the nonvolatile remainder of the fluorinated composition by heating said composition to the volatilization temperature of said plutonium fluoride leaving a residue comprising essentially nonvolatile fission product fluorides, and recovering said volatile plutonium fluoride.

30 9. In a process for the recovery of plutonium tetrafluoride in concentrated and purified form from a solid composition containing columbic oxide, plutonium values, and fission product values, the steps which comprise contacting said composition with anhydrous hydrogen fluoride to form plutonium tetrafluoride, columbium pentafluoride, and fluorides of said fission products, separating said plutonium tetrafluoride from said columbium pentafluoride and volatile fission product fluorides by heating the hydrofluorinated mass to the volatilization temperature of said columbium pentafluoride and volatile fission product fluorides, leaving a nonvolatile residue comprising plutonium tetrafluoride and nonvolatile fission product fluorides.

40 10. In a process for the recovery of plutonium tetrafluoride in concentrated and purified form from a solid composition containing columbic oxide and plutonium values, the steps which comprise contacting said composition with hydrogen fluoride and heating the resulting hydrofluorinated mass to the volatilization temperature of the columbium pentafluoride thus produced, leaving as a nonvolatile residue a composition comprising plutonium tetrafluoride.

50 11. In a process for the recovery of plutonium tetrafluoride in concentrated and purified form, the steps which comprise contacting an aqueous medium containing plutonium in a valence state not greater than 4 with columbic oxide, separating the resulting solid composition comprising plutonium values and columbic oxide, thereafter contacting said composition with hydrogen fluoride, and heating the resulting hydrofluorinated mass to the volatilization temperature of the columbium pentafluoride thus produced leaving as a nonvolatile residue a composition comprising plutonium tetrafluoride.
